UNITED STATES PATENT OFFICE

1,972,269

DERRICK CONSTRUCTION

Arthur W. Lewis, La Canada, Calif.

Application November 17, 1933, Serial No. 698,415

6 Claims. (Cl. 189—13)

My invention relates to steel derricks of the character employed in oil well drilling, and is an improvement on the invention disclosed in my Patent No. 1,935,095 for Derrick construction issued November 14, 1933.

Steel derricks as ordinarily constructed are quite expensive. My present invention has for an object to produce a material saving in the cost of steel derricks without in any way impairing the features found in the commonly accepted types of construction. I have found that by a new method of arranging the girts and diagonal struts a material economy can be attained in the construction of a derrick, such new arrangement of parts consisting of placing the girts across pairs of legs of the derrick in a manner to form vertically adjacent panels which are substantially rectangular in form and placing the diagonal reinforcing struts across the corners of these panels so as to form centrally within the panel a quadrilateral figure having its diagonal axes directed vertically and laterally. Such arrangement I have disclosed in my co-pending application above set forth.

My present invention has as one of its principal features an arrangement of the above set forth reinforcing members which will enable the forming of proper openings or doorways at the bottom of the derrick and yet maintain a structural continuity. For example, it is customary to employ in conjunction with the derrick a walking beam and associated equipment which extend through a relatively high doorway at one side of the structure and rotary draw-works equipment mounted in a doorway or opening of less height formed in an adjacent side of the derrick. My present invention involves the vertical offsetting of the panels in one side of the derrick relative to the panels in the other side of the derrick in such a manner that ample and economical reinforcement of the derrick is maintained due to the characteristic manner in which the girts, struts, and legs of the derrick are tied together, thereby enabling the forming of doorways of different heights in adjacent sides of the derrick in a very simple manner.

Further objects and advantages of the invention will be brought out in the following part of the specification.

Referring to the drawing, which is for illustrative purposes only,

Fig. 1 is a perspective view looking toward one corner of a derrick made in accordance with my invention.

Fig. 2 is a view looking toward the diagonally opposite corner of the derrick.

Fig. 3 is an enlarged fragmentary view showing a manner of connecting the upper and lower ends of the diagonal strut members to intermediate portions of girts.

Fig. 4 is a fragmentary perspective view showing the interconnection of a leg, the end of a girt, and the lateral ends of diagonal strut members.

In view of the fact that methods of attaching structural members are well known to the arts, parts of a derrick are illustrated in Figs. 1 and 2 by single lines. The derrick shown for illustrating a preferred embodiment of my invention has the general form adopted for oil well drilling practice and comprises four legs 10, 11, 12, and 13 mounted on a rectangular base 14 and converging upwardly so as to define a space or central shaft portion which is essentially vertical and is of rectangular cross section. As shown in Fig. 4, each of the legs may be made from a pair of angle members 15 suitably secured together by means of bolts 16 or rivets and in such a manner that the legs 17 thereof lie in adjacent vertical planes of the derrick sides. The legs 11 and 12, as shown in Fig. 1, may for the purpose of explanation be said to define a front side 18 of the derrick; the legs 10 and 13, as shown in Fig. 2, the rear side 20 of the derrick; the legs 10 and 11, as shown in Fig. 1, a lateral side 21 of the derrick; and the legs 12 and 13, as shown in Fig. 2, the remaining lateral side 22 of the derrick. Also, for the purpose of explanation the front side 18 and the lateral side 21 of the derrick may be considered corelatively primary and secondary sides, and the sides 20 and 22 of Fig. 2 may be also considered primary and secondary sides. In fact, it will be later perceived from the explanation that any two adjacent sides may be properly considered to be in primary and secondary relation.

Referring to Fig. 1, laterally directed girts 24 are in vertically spaced relation extended across the primary or front side 18 of the derrick, the ends of these girts being connected to the legs 11 and 12 and dividing the essentially vertical plane in which the legs 11 and 12 reside into a plurality of approximately rectangular areas or panels 25. The rear side of the derrick is likewise divided into a series of consecutive vertical panels 25a by means of girts 24a, the spacing of the girts 24a being the same as the spacing of the girts 24 so that each girt 24 will operate in paired relation to a girt 24a to define a horizontal plane. Each of the panels 25 and 25a is reinforced by use of a

set of four diagonal bracing members 26, each of which members 26 is placed across a corner of the quadrilateral area or panel 25 or 25a in a manner to form within the four strut members 26 a rectangular area in an on-end relation, or, in other words, with one diagonal axis thereof extending vertically and the other diagonal axis thereof extending laterally. The upper and lower ends 27 and 28 of the diagonal reinforcing members 26 are secured to central portions of the girts 24-24a in a manner such as illustrated in Fig. 3, and the lateral ends 30 of the diagonal reinforcing members 26 are secured to a leg of the derrick in a manner such as illustrated in Fig. 4, the point of joining of the ends 30 with the leg being located approximately centrally between two adjacent girts.

In the horizontal planes defined by the lateral corners of the rectangular figures defined by the struts 26, girts 32, which may be considered in secondary relation to the girts 24 and 24a, are connected between the legs 10 and 11, as shown in Fig. 1, and similar secondary girts 32 are connected between the girts 12 and 13, as shown in Fig. 2. Accordingly, the girts 32 are vertically offset from the girts 24 and 24a a distance substantially half the vertical spacing of the girts 24 and 24a, and the secondary girts 32 form in the planes defined by the legs 10-11 and 12-13 approximately rectangular panels 33 which may be considered in secondary relation to the panels 25 and 25a for the reason that they are offset relative thereto.

As shown in Fig. 3, the upper and lower ends 28 and 27 of the struts 26 may be connected to the central portion of a girt, such as the girt 24, by means of a plate 34 which may be secured to the girt by means of bolts 35. The ends 27 and 28 may be secured to the plate 34 by attachment means 36 including bolts 37. It will be perceived that at every point of interconnection, such as shown in Fig. 3, there is a six-point connection between the structural parts which extend outwardly along the six center lines 38 which radiate from the center point P. As shown in Fig. 4, the end 40 of each girt in the main portion of the derrick structure has five-point connection with a derrick leg and the lateral ends 30 of a pair of struts 26. In other words, there are structural members extending from a point P' in five directions, as indicated by radial center lines 41.

In the construction above described, horizontal stresses in the derrick structure are carried entirely around the derrick structure along the lines of interconnected strut or girt members. For example, a force acting horizontally, as shown by the arrow 42 in Fig. 1, against the girt specifically designated as 24b will be transmitted from the center of the member 24b through struts 26a to the rightward ends of girts 24c and from the leftward end of the girt 24b through struts 26b to the center of the girts 24c. Accordingly, there is a well defined interconnection between girts, through use of the struts, entirely around the derrick.

Also in my present structure the ideal structural arrangement or reinforcing of panels as above set forth may be carried very close to the lower end of the derrick structure and still permit the formation of doorways or openings such as indicated at 44 and 45, Fig. 1. The girt 24d forming the lower extremity of the first panel in the front side 18 of the derrick may be disposed so as to define the upper end of the opening or doorway 44 which is of a height H suffi-

cient to accommodate the walking beam or percussion drilling means employed in well drilling work. In an adjacent side of the derrick, such as the lateral side 21, the opening 45 is provided for accommodation of other drilling equipment, such as the rotary draw-works. This opening need not be as tall as the opening 44 and accordingly may have a height h, the result being that the lowermost panel of the lateral side 21 of the derrick may start with the girt 24e which is downwardly offset from the girt 24d.

Diagonal reinforcing means, other than the preferred type of diagonal reinforcing means set forth above, is in this construction required to a much smaller extent than in my former construction, which results in definite structural advantages and savings in material. The opening 44 may be defined by diagonal reinforcing struts 46 which extend between the lower ends of the legs 11 and 12 and the central portion of the girt 24d, having in conjunction therewith auxiliary bracing members 47 and 48. To diagonally brace the lower extremity of the lateral side 21 of the derrick, diagonal struts 50 may be carried from the lower ends of the legs 10 and 11 across the girt 24e to connect with the central portion of the girt 24d above the girt 24e. It is to be understood that the struts 50 are tied to the structural members, such as the girt 24e, which they cross.

As shown in Fig. 2, the rear side 20 of the derrick may have an opening 44a formed at the lower end thereof in accordance with the means disclosed in Fig. 1 to form the opening 44. The side 22 of the derrick, Fig. 2, may be with or without an opening or door means at the lower end thereof, as desired.

In exceptionally tall derricks and in those for use under severe working conditions, it may be desirable to employ auxiliary bracing members 52 in some of the panels near the lower end of the derrick structure. These auxiliary braces each have one end thereof connected to a central portion of a strut 26 and the other end connected to a corner structure of a panel in accordance with the disclosure of my prior application hereinbefore set forth.

Although I have herein shown and described my invention in simple and practical form, it is recognized that certain parts or elements thereof are representative of other parts, elements, or mechanisms which may be used in substantially the same manner to accomplish substantially the same results; therefore, it is to be understood that the invention is not to be limited to the details disclosed herein but is to be accorded the full scope of the following claims.

I claim as my invention:

1. An oil well derrick of the character described, including: a complement of substantially vertical leg members placed in upright position and cooperating in pairs to form adjacent sides of the derrick; primary girts extending across a primary side of said derrick between adjacent leg members in vertically spaced relation to form a vertical series of panels; secondary girts extending across a secondary side of said derrick adjacent said primary side, said secondary girts being spaced in vertically offset relation to said primary girts so as to form a vertical series of panels vertically offset from said panels of said primary side of said derrick; and diagonal struts placed across the corners of said panels so as to substantially define centrally of said panels quadrilateral figures having their diagonal axes crossing in horizontal and vertical directions.
